UNITED STATES PATENT OFFICE

2,477,708

GASOLINE CONSERVING POWER INCREASING VAPORIZER

**John Carl Wichmann and Neil Orr Wichmann,
Los Angeles, Calif.**

Application June 2, 1947, Serial No. 751,770

2 Claims. (Cl. 123—25)

2 Claims. (Cl. 123—25)

1. What is the relationship between the two variables?

ates to a supercharging plug valve 26 controlled by a piston 27.

Vaporizer,
section with
strainer and
Leading

Our invention relates to a supercharging gasoline conserving power increasing vaporizer, particularly designed for use in connection with internal combustion engines and one of the principal objects of our invention, is to generally improve upon and simplify the gaseous fuel supply systems shown in our copending application for U. S. Letters Patent filed July 29, 1944, Ser. No. 547,259, also application filed May 20, 1946, Ser. No. 671,042.

A further object of our invention is, to provide a simple, highly effective and easily adjusted and controlled system for delivering to the carbureted air passing from the carburetor to the intake manifold, a heated vaporized mixture of properly proportioned oil, oil vapor, air and water, in order to materially increase the power output of the engine with which the equipped carburetor is associated, also conserving gasoline consumption, minimizing the development of carbon in the valve and piston chambers, eliminating tendency of the motor to "ping" or knock while in service, providing for easy starting and quick acceleration, also, cooler and smoother running of the motor and achieving economy in fuel costs, due to the ability to operate the motor effectively with the lower grades of gasoline.

With the foregoing and other objects in view, our invention consists in certain novel features of construction and arrangement of parts which will be hereinafter more fully described and claimed and illustrated in the accompanying drawings in which:

Fig. 1 is a diagrammatic elevational view with parts in section of our improved system and showing same associated with an internal combustion engine and its carburetor.

Fig. 2 is an enlarged vertical section taken on the line 2—2 of Fig. 1.

Figs. 3 and 4 are detail sectional views of certain check valves used in our improved system.

Referring by numerals to the accompanying drawings, which illustrate a preferred embodiment of the invention, 10, designates the engine cylinder block, 11, a portion of the crank case, 12, an air filter, 13, the carburetor and 14, an adapter ring located between the carburetor and intake manifold 15. A pump 16 forces gasoline through a duct 17, having portions located adjacent block 10, to and through a strainer 18 and duct 19, to carburetor 13.

duct 13, to carburetor 15.

Leading from the water chamber of block 10, to a strainer 21 is a duct 22, and leading from the latter to a housing 23, having an inwardly opening check valve 24, is a duct 25. A screw

plug valve 26 controls the flow of water into strainer 21.

Leading from the chamber within crank housing 11 below the normal oil level therein, to a strainer 27, equipped with a screw plug valve 28, is a duct 29 and leading from strainer 27, to housing 23 above the valve 34 therein, is a duct 30.

Leading from valve housing 23 to a duct 31, is a duct 32 having a flow control valve 33 and said duct 31, equipped with a flow control valve 34, leads to adapter ring 14.

Leading from the upper portion of the air chamber in crank case 11, above the oil level therein, to a housing 35, having an inwardly opening check valve 36, is a duct 37 and located in a vertical portion thereof, adjacent the crank case is an oil trap 38.

Leading from housing 35 above the valve therein, is a duct 39 which is connected by means of a three way coupling, to ducts 31 and 32. A coupling 40 connects duct 39 to a valve housing 41, having an inwardly opening check valve 42 and connected to said valve housing in front of the valve therein, is an open ended air inlet fitting 43.

25 fitting 45. A fitting which serves as a crank case ventilator and oil funnel, comprises an upright housing 44, carried by an axial tube 45, the open lower end of the latter entering the top of the chamber 30 in the crank case and the upper end of said tube being flared outwardly against the wall of said housing. Surrounding tube 45 in the lower portion of the housing is a partition 46 provided with a plurality of apertures 47 and formed through the wall of housing 44 below said partition, is an air inlet aperture 48.

The chamber between housing 44 and tube 45 above partition 46 is filled with air filtering material 49, preferably fibrous, and formed throughout the upper portion of the wall of said tube are apertures 50 (see Fig. 2).

During engine operation, pump 16 forces liquid gasoline through duct 17 to and through gasoline strainer 18 and 19 to carburetor 13 wherein the air from air filter 12 is carbureted and passes through adapter ring 14 into and through adapter ring 14 into and through the intake manifold leading to the engine cylinders. Considerable suction produced in the intake manifold will, as the various check valves in the system are opened, prevails in ducts 22, 25, 30, 32, 39, 43 and 31 and the various fittings associated therewith and thus air will be drawn through fitting 43, past check valve 42 in housing 41, and then through ducts 39 and 31.

Simultaneously, oil vapor and air will be drawn from the crank case through duct 37 past check valve 36 in housing 35 and then through duct 39 to duct 31.

Any liquid oil drawn into duct 37 will, in passing through trap 38 separate from the vapor and drop back into the crank case and at the same time, moisture, either cool or hot water, will be drawn from the water chamber of the motor block 10 through duct 22, strainer 21, duct 25, 10 duct 30, past check valve 24 and thence through open valve 30 and duct 32, to duct 31.

Simultaneously, heated oil will be drawn from the crank case 11 through duct 29, strainer 27, duct 30, past check valve 24, and thence through 15 valve 33 and duct 32 to duct 31.

Thus air, oil, oil vapor and moisture, either cool or hot water are simultaneously drawn into duct 31, and after mixing through the moisture passes into the intake manifold of the engine to 20 mix with and materially reinforce the carbureted air flowing from the carburetor to said intake manifold and the combustion chambers of the engine.

Obviously, this intimate mixture of carbureted air, moisture, atmospheric air, oil, vapor, oil mixture, greatly enhances the development of power as said mixture is ignited and burns in the combustion chambers of the engine and at the same time, perfect lubrication for the valves, valve 25 stems, piston heads and cylinder walls is assured.

By taking moisture from the water circulation chamber of the engine block and withdrawing oil and oil vapor from the crank case, the necessity for separate water and oil containers and the periodic servicing thereof is eliminated.

To insure best results, the valves 26 and 28 are barely "cracked" or opened to only a slight degree, and valve 34 is regulated to control the volume flow of the mixture to the intake manifold. 40

Thus it will be seen that we have provided a gasoline conserving power increasing vaporizer for internal combustion engines, which is simple in structure, inexpensive of manufacture and very effective in performing the functions for which it is intended.

Minor changes in the size, form and construction of the various parts of our improved gasoline-conserving power increasing vaporizer may be made and substituted for those herein shown and described without departing from the spirit of our invention, the scope of which is set forth in the appended claims.

We claim as our invention:

1. The combination with a carburetor, an engine cylinder block and crank case, of a duct leading to the carbureted air outlet from said carburetor, means for conducting moisture from the water jacket of said cylinder block to said duct, means for conducting oil and oil vapor from the crank case to said duct and a combined oil funnel, ventilator and air filter communicating with the chamber in said crank case.

2. The combination as set forth in claim 1 with an oil trap in the oil vapor conducting means.

JOHN CARL WICHMANN,
NELL ORR WICHMANN.
